UNITED STATES PATENT OFFICE.

ALBERT W. MORSE AND WALTER E. WOLLHEIM, OF NEW YORK, N. Y.; SAID WOLLHEIM
ASSIGNOR TO THE ANTHONY COMPANY, OF LONG ISLAND CITY, NEW YORK, A COR-
PORATION OF NEW YORK.

STRAINER.

Application filed July 30, 1927. Serial No. 209,455.

This invention relates to strainers for liquids and is particularly adapted for use in fuel oil systems.

It is one of the objects of the invention 5 to provide a structure for a strainer of this kind with a duplicate set of strainer screens for the arresting of dirt or other foreign particles in the liquid, and is equipped with means by which one of the strainer screens 10 may be cut out for cleaning or repairing without interrupting the flow of the liquid through the other screen. Another object is to provide in a structure of this kind a single air or steam blow-out connection which 15 in combination with the peculiar construction of the cut-out means admits the air, steam or other purging medium to clean or blow out that particular strainer screen only which is not in use. A still further object 20 is to make the operation of the cut-out means very simple and by its direction of its handling mechanism indicate which of the two strainer screens is in use. Still other objects will become apparent in the 25 following specification and the accompanying drawings forming a part thereof.

In the drawings,

Fig. 1 is a vertical sectional view through the strainer structure showing a preferred 30 embodiment of the invention;

Fig. 2 is a horizontal sectional view along the plane of line 2—2 in Fig. 1;

Fig. 3 is a horizontal sectional view along the plane of line 3—3 in Fig. 1; and

Fig. 4 is a vertical cross sectional view 35 along the plane of line 4—4 in Fig. 3.

Like characters of reference denote similar parts throughout the several views and the following specification.

10 is a hollow casing of substantially oblong shape. 11 is a bridge wall extending across the upper part of the inside of the casing 10 dividing the same into a lower or inlet chamber 12 and an upper or outlet 15 chamber 13. Symmetrically disposed at each side of the top of the casing 10 is a hollow cap 14, closed at its top, projecting through the outlet chamber 13, and being threaded into the wall 11 at 15, a shoulder 16 making a tight seat against the top of the casing. The vertical wall of the cap 14 between the top of the casing and its wall 11 is provided with openings 17. The lower open end of cap 14 terminates in a

cylindrical extension 18 somewhat smaller 55 in its outer diameter than the threaded portion 15. 19 is a cup-shaped strainer basket made of perforated sheet metal or the like, having its open end fitted tightly over the extension 18.

Casing 10 is provided at its front with a cylindrical extension 20, internally threaded at 21 for a pipe, in communication with the outlet chamber 13 by passages 22, 23 and 24. Casing 10 is provided with a 60 similar extension 25 at its back, similarly threaded at 26, this extension being in communication with the inlet chamber 12 by 65 passages 27, 28, 29 and 30.

31 is a tapering cut-out key, rotatably 70 fitted in the casing 10, preferably centrally between caps 14, between its top wall 11 and its bottom wall. 32 is a solid wall extending across the central part of the key 75 31 about in line with wall 11 of the casing 10. The upper part of the key 31 between the top wall of casing 10 and wall 11 has a substantially rectangular opening 33 into a hollow center 34. This opening is of 80 such width that it forms a continuous passage from opening 23 to opening 22, or from opening 24 to opening 22 when rotated $\frac{1}{4}$ revolution. Attention is particularly drawn to the fact that when openings 23 and 22 85 are in communication through hollow center 34, a solid wall 35 of the key 31 closes opening 24, and vice versa, when rotated $\frac{1}{4}$ revolution, wall 35 closes opening 23, while openings 22 and 24 are registering through 90 the hollow center 34. The lower part of the key 31 terminates in a solid end 36 fitted tightly in the bottom wall of the casing 10. A vertical central partition 37 connects 95 wall 32 with end 36 of the key 31. This partition is so disposed that it connects openings 28 and 29 while cutting out opening 30 when the upper part of key 31 connects openings 22 and 23, and similarly connects openings 28 and 30 and cuts out opening 29 when rotated $\frac{1}{4}$ turn, while its upper 100 part connects openings 22 and 24. 38 is an outwardly projecting spindle of key 31 having its terminal D-shaped to receive a correspondingly shaped socket of a handle bar 105 39. This bar has a downwardly projecting lug 40 adapted to travel along side the front of the casing 10 in a segmental path 41 and is limited in its travel to a $\frac{1}{4}$ rev-

lution by the ends 42 of the path 41 which is partially cut in the outer wall of casing 10. 42^a is a bonnet over spindle 38 screwed into the top of casing 10 and 43 is a stuffing box nut. 44 is a spring pressing against the top of the cut-out key 31 to cause its sides to fit tightly against their bearings in casing 10.

In the rear of the casing on top of extension 25 is a boss 45 threaded to receive an elbow connection 46 and a valve 47. 48 is a circumferential groove in part of the upper wall 35 in communication with boss 45 and connection 46 through an angularly disposed duct 49. This groove is so arranged as to register with opening 24 only when the same is cut off from registering with opening 22 by wall 35, and similarly, when key 31 is rotated $\frac{1}{4}$ turn, groove 48 registers with opening 23. In both positions, however, groove 48 is in communication with elbow connection 46 through duct 49.

50 are clean-out plugs in the bottom wall of casing 10 below each of the strainer baskets 19. A similar plug 51 is provided below the cut-out key 31 for the purpose of facilitating the machining of the casing 10.

The operation of the strainer is as follows:

When the strainer is in the position shown in the drawings, oil or other liquid to be strained is admitted under pressure through a pipe screwed into extension 25, thence through duct 27 and opening 28, past wall 37 of the lower part of the key 31 and opening 29 into the lower or inlet chamber 12, at the left side of casing 10. The oil then passes through the strainer basket 19 which being of very fine mesh causes any impurities or other foreign matter to accumulate around its outside. The clean oil is forced through the openings 17 in the cap 14 into the upper or outlet chamber 13 at the left side of the casing and thence through opening 23 into the hollow upper center 34 of the key 31, and thence through opening 22 into a pipe screwed into extension 20. Openings 22 and 23 and openings 28 and 29 are of substantially the same area, as are also the passage for the oil through hollow center 34 and the space alongside partition 37. The passages in the upper part of the key 31 and openings 22 and 23 are wider and shorter than the passages in the lower part of the key and openings 28 and 29 which are relatively longer and narrower because of the tapering shape of the key and the importance of keeping these passages of a uniform area.

Attention is now particularly drawn to the fact that in the position indicated in the drawings and just now described, oil is admitted into the left side of the casing and discharged therefrom by virtue of the cut-out key 31 which deflects the flow of oil to and from that side of the casing, and that 65 the handle bar 39 is so attached to the spin-

dle 38 of the key 31 that it points toward the left side of the casing which serves to indicate that the left side strainer is functioning as such. The lug 40 is pushed tightly against the left hand terminal 42 of its travel. In this position, openings 24 and 30 at the right side of the casing adjacent the key 31 are cut out by, respectively, walls 35 and 37. Opening 24 is symmetrically disposed at the right side of key 31 to opening 23 and is of the same size and, similarly, opening 30 to opening 29. No oil therefore passes into the right hand side of the casing and through the right hand strainer basket 19. The right hand strainer can now be cleaned easily by admitting steam through valve 47 (which is piped to a steam line), elbow connection 46, duct 49 and groove 48 into the inlet chamber 12 at the right hand side of the casing and through openings 17 into the inside of the strainer basket. Here it forces all foreign matter around the outside of the basket away from the screen and blows it out through the opening at the bottom from which the clean-out plug 50 has been removed. This blowing out can be achieved very efficiently, because the steam is blown through the strainer mesh in a direction opposite to the normal flow of the oil whereby all sediment caked around the outside of the basket is very quickly loosened. The groove 48 does not communicate with the left hand side of the strainer; therefore steam does not enter that side and its functioning is not interfered with.

By giving the handle bar 39 a $\frac{1}{4}$ turn to the right to the end of its travel as fixed by lug 40, the above described position and functioning is exactly reversed, and instead of the left hand strainer working and the right hand strainer being cut out, the right hand strainer is working and the left hand strainer cut out. The handle bar 39 pointing toward the right side of the casing indicates that the right hand strainer is functioning. In this position then, the left hand strainer basket can be blown out exactly in the manner described before in reference to the right hand strainer basket. In other words, that strainer which is cut out of service can be cleaned by simply opening the single steam valve attached to the casing and permitting the steam to blow out the impurities through an opening at the bottom of the strainer. It is impossible to admit steam into the working strainer, but the peculiar arrangement of steam passages permits only of cleaning that strainer which is cut out of service. While I have referred herein and in the appended claims to the purging medium as being steam, I do not want to be limited to steam only, but any other suitable purging medium, either liquid or gaseous, such as air or water for instance, may be employed equally as well, and the 130

term "steam" is to be interpreted broadly.

It is understood that various changes in the form, proportion and minor details of construction may be resorted to without departing from the principle or sacrificing any of the advantages of the invention as defined in the appended claims.

What we claim as new, is:

1. A strainer for liquids comprising a structure having an inlet, an outlet and a steam connection, a pair of strainer screens interposed in passages between the said inlet and outlet, and a key having means for shutting off one of the screens from the said inlet and outlet and means for admitting steam from the said steam connection to that screen only which is shut off.
2. A strainer for liquids comprising a structure having an inlet, an outlet and a steam connection, a pair of strainer screens interposed in passages between the said inlet and outlet, and a key having means for alternately shutting off one of the screens from the said inlet and outlet and admitting steam from the said steam connection to that screen only which is shut off, and a blow-out connection for the steam, near the screen, to carry off accumulated sediment.
3. A strainer for liquids comprising a structure having an inlet, an outlet and a steam connection, a pair of strainer screens interposed in passages between the said inlet and outlet, and a key having walls and passages adapted to alternately shut off one of the screens from the said inlet and outlet and to admit steam from the said steam connection to that screen only which is shut off, and a blow-out connection for the steam, near the screen, to carry off accumulated sediment.
4. A strainer for liquids comprising a structure having an inlet, an outlet, and a steam connection, a pair of strainer screens interposed in passages between the said in-

let and outlet, a key having means for shutting off one of the screens from the said inlet and outlet and means for admitting steam from the said steam connection to that screen only which is shut off, and a handle bar exterior of the said structure for operating the said key indicating by its direction that strainer screen which is not shut off.

5. A strainer for liquids comprising a structure having an inlet, an outlet and a steam connection, a pair of strainer screens interposed in passages between the said inlet and outlet, a key having means for shutting off one of the screens from the said inlet and outlet and means for admitting steam from the said steam connection to that screen only which is shut off, and a handle bar exterior of the said structure for operating the said key having means for limiting its travel, the said key being adapted to shut off one of the said strainer screens at one end of its travel and the other screen at the other end of its travel, the said handle bar indicating by its direction that strainer screen which is not shut off.

6. A strainer for liquids comprising a structure having an inlet, an outlet and a steam connection, a pair of strainer baskets interposed in passages between the said inlet and outlet so that the liquid from the inlet will be admitted around the outside of the basket to the inside thereof and thence to the outlet, and a key having means for shutting off one of the baskets from the said inlet and outlet and means for admitting steam from the said steam connection to the inside of that strainer basket only which is shut off, and a blow-out connection near this said basket.

In witness whereof we have hereunto set our hands.

ALBERT W. MORSE.
WALTER E. WOLLHEIM.
